BLOWTORCH WITH VERTICAL RETORT

Leo J. Cieminski, Chicago, Ill.

Application August 7, 1944, Serial No. 548,391

1 Claim. (Cl. 158—33)

1

This invention relates to improvements in hydrocarbon fuel furnaces. More particularly, it pertains to a hydrocarbon fuel pressure tank furnace construction, of the blow torch type, and includes correlated improvements and discoveries involving a novel arrangement of structure whereby the operation of such a device is considerably enhanced.

In conventional furnaces, or blow torches of this type, operators have been finding it increasingly difficult to keep the burner unit clean. Particularly is this true because of the fact that the most available and popular type of fuel in use today, namely, gasoline, now contains, with few exceptions, an anti-knock substance, such as tetraethyl lead. Such fuels are conducive to clogging the orifice in the burner head of the burner unit, and especially that section of pipe leading from the fuel supply conduit which is utilized to vaporize the fuel entering the burner head. When such burners and pipes become clogged, inefficiency and often failure in operation results and it is necessary to dismantle the burner for cleaning purposes or, as in the case of the vaporizing members which heretofore have been coiled or otherwise tortuously wound, to discard them entirely.

It would be a distinct advantage to be able to clean such members as the burner head quickly and automatically whether or not the device is in operation, as well as to maintain the vaporizers in a clean and efficient operating condition by so constructing and arranging them with respect to the burner as to make replacement and cleaning easy and simple without discarding them after normal periods of use, and this can be accomplished by means of the present invention.

Generally, it is an object of the present invention to provide a burner unit for a blow torch which is simple, yet sturdy and durable as well as economic of construction and operation, and which will operate with relative freedom from wear and tear and other mechanical difficulties and disadvantages.

A principal object of the invention is to provide a hydrocarbon fuel pressure tank furnace construction, of the blow torch type, with a burner unit preferably suspended above the tank from an upwardly directed fuel supply conduit communicating therewith, the unit comprising a downwardly directed fuel vaporizing member with a burner head secured to the lower end of the vaporizing member and a combined fuel and clean-out control valve cooperatively associated with the burner head.

2

More specifically, it is an object of the invention to provide, in a hydrocarbon fuel pressure tank furnace construction of the blow torch type, a burner unit suspended above the tank from an upwardly directed fuel supply conduit, the unit including a downwardly directed fuel vaporizing member disposed in a substantially vertical position with an offset burner head secured to the lower end of the vaporizing member with a fuel control valve disposed within the offset portion of the burner head, and a protective burner shell carried by the offset burner head and surrounding the vaporizing member to protect and to confine the flame emanating from the burner head to a restricted area encompassingly to heat the vaporizing member.

Another object of the invention is the provision, in a furnace construction of the blow torch type, of a burner head which has disposed therein a combination fuel control valve and clean-out member comprising a control valve needle and an endwise extension on the needle aligned with a fuel orifice in the burner head and cooperatively associated therewith in a manner whereby the orifice can be kept clean and unobstructed upon opening and closing the control valve.

Other objects of the invention will in part be obvious and will in part appear hereinafter.

30 The invention accordingly comprises the features of construction, combination of elements, and arrangement of parts, which will be exemplified in the construction hereinafter set forth and the scope of the application of which will be indicated in the claim.

35 For a fuller understanding of the nature and objects of the invention reference should be had to the following detailed description taken in connection with the accompanying drawing, in which:

40 Fig. 1 is an elevational view showing, by way of illustration, a blow torch, such as a plumber's furnace, equipped with a burner unit embodying the present invention;

45 Fig. 2 is a sectional elevational view, with parts broken away, illustrating an actual size burner unit of the kind utilized in a furnace such as that depicted in Fig. 1;

50 Fig. 3 is a view similar to Fig. 2 taken along the line 3—3 thereof and looking in the direction of the arrows; and

55 Fig. 4 is a transverse sectional view taken along the line 4—4 of Fig. 3 and looking in the direction of the arrows.

Referring more particularly to the drawing,

there is indicated generally at 10 a conventional type of fuel furnace having a pressure tank 11 which can be filled through a filler cap 12 with a suitable hydrocarbon fuel such as gasoline. The pressure in the tank 11 is maintained by a conventional type of pump 13 to force the fuel upwardly into a fuel supply conduit 14 controlled by a valve 15.

A burner unit indicated generally at 16 is suspended above the tank 11 from the fuel supply pipe 14. The burner unit 16 comprises a downwardly directed fuel vaporizing member, or pipe, 17, which preferably is disposed in a substantially vertical position. This pipe preferably is equipped with a fuel baffle, or agitating member, 18, which preferably is in the form of a tortuously gathered wire. This wire serves to enhance the vaporizing characteristic of the pipe 17 and makes cleaning thereof more facile as will more fully appear hereinafter.

At its upper end the vaporizer 17 is in communication with the upwardly directed fuel supply pipe 14 by means of a connecting pipe 19 which also contains a tortuously wound wire, 20, similar to that illustrated at 18 in the vaporizer pipe 17.

At its lower end the vaporizer pipe 17 is screw-threaded to a burner head 21. The particular burner head illustrated has an offset portion 22. Within the offset portion is disposed a hydrocarbon fuel flow control needle valve 23 which is screw-threaded into an extension 24 of the offset portion of the burner head. The burner head is equipped with a removable valve member 25 having a burner orifice 26. The needle valve 23 has an endwise extension 27 which is adapted to pass through the burner orifice 26 when the needle control valve is operated by means of the hand wheel 28. A hydrocarbon fuel passageway 29 in the burner head 21 connects the vaporizer pipe 17 with a fuel chamber 30 in the offset portion of the burner head.

A burner shell 31 is carried by the burner head preferably by being secured to the extension 24 by means of a suitable lock washer 32. It will be observed that the burner head surrounds the vaporizing pipe to protect and to confine the flame which emanates from the burner head to a restricted area and to direct the heat in such a manner as to encompass the vaporizing pipe. Preferably, the vaporizing pipe 18 extends along one inner wall of the shell 31. Being closed at its bottom, the shell provides a priming cup having primary air inlets 33 extending above the same. Preferably the shell is cylindrical in contour and is flared inwardly at the top to provide a constricted outlet 34 adjacent the zone of combustion. The size of the opening or outlet 34 is so chosen, for example, that it controls the amount of air passing through the primary air inlets 33 and this tends to control the zone of combustion for optimum operating efficiency with respect to the vaporizing member.

Depending from the bottom of the shell 31 are two lugs 35 and 36 which serve to protect the control valve after it has been set for a particular operation. These projections serve to prevent the valve from accidentally being turned so as to change the rate of fuel flowing into the valve chamber 30 whereby the flame of the torch is kept constant, and also serve to protect the valve control portions from being broken or bent through rough usage.

Such a burner unit has many advantages, such as, the particular vaporizer structure and the fuel control and clean-out valve associated therewith.

by means of the particular burner head as illustrated. For example, when foreign matter accumulates in and around the burner orifice 26, due either to carbon, dirt or the type of gasoline used, as the tetraethyl lead heretofore mentioned, it is but necessary to move the valve stem 32 in an endwise direction so that the endwise extension 27 on the valve needle 23 will pass into and out of the orifice, thereby cleaning the same. The foreign matter will be ejected outwardly of the burner head and the operation of this type of combination valve can be performed during the time the torch is in use. The simplicity in construction of this type of valve, as well as the burner head, is a further advantage which should be taken into consideration because of its ease of assembly as occasion may require. A further distinct and primary advantage lies in the simplified structure of the vaporizing arrangement and its associated parts. For example, the vaporizer pipe is not of the coiled type and can readily be unscrewed from position so that carbon and other foreign materials which have accumulated therein can easily be removed therefrom. It is not necessary to discard such vaporizer pipes and they can be re-used.

It is important also that such a vaporizer can be brought down into the burner shell without difficulty where it lies adjacent the interior wall so that vaporization is readily effected because of the close proximity of the burner flame and the reflected heat against the inner wall. Such an arrangement makes it unnecessary to use the cumbersome coil or otherwise tortuously wound arrangements of conventional devices heretofore disposed at remote places from the burner flame. The straight pipe is particularly adapted for the use of baffle or agitator means such as the wires 18 and 20 in the pipes 17 and 19 respectively. These wires serve not only to break up the stream of fuel coming from the fuel supply pipe 14 but aid in vaporization because they collect and hold additional heat. Also, they can readily be removed and cleaned and in doing so carbon and other accumulated matter is simultaneously removed. These wires can also readily be replaced and re-used from time to time.

It will thus be seen that the objects hereinbefore set forth may readily and efficiently be attained and since certain changes may be made in the above described construction and different embodiments of the invention could be made without departing from the scope thereof, it is intended that all matter contained in the above description, or shown in the accompanying drawing, shall be interpreted in an illustrative and not in a limiting sense.

Having described my invention, what I claim as new and desire to secure by Letters Patent is:

In a hydrocarbon fuel pressure tank furnace construction of the character described, the improvement which comprises a burner unit disposed above said tank and connected to an upwardly directed fuel supply conduit communicating therewith, said unit comprising a downwardly directed fuel vaporizing member disposed in a substantially vertical position, an offset burner head secured to the lower end of said vaporizing member, said offset burner head having an extension which is perpendicular to said vaporizing member, a fuel control valve substantially vertically disposed within the extension offset portion of said burner head, and a protective burner shell carried by said offset burner head and surrounding said vaporizing member.

to protect and to confine the flame emanating from said burner head to a restricted area to heat said vaporizing member, said valve having a clean-out member comprising a control valve needle and an endwise extension on said needle aligned with a fuel chamber and a fuel burner orifice in the burner head and adapted to penetrate said burner head whereby said orifice and chamber can be kept clean and unobstructed upon continuous operation of said apparatus, and a plurality of oppositely disposed fingers extending from the bottom of said shell to shield the fuel control valve against injury and to maintain its regulated operating position and to permit ready access to the valve control further to regulate the same and clean the valve opening while the device is in operation.
